WIRE SPLICING TOOL

Lorence O'Russo, Princeville, Ill., assignor to
Mathias Klein & Sons, Chicago, Ill., a corpora-
tion of Illinois

Application June 5, 1933, Serial No. 674,335

5 Claims. (Cl. 140—119)

My invention relates generally to wire splicing tools, and more particularly to ratchet type sleeve twisters.

At present it is common practice to secure the ends of a pair of conductors together by passing a copper or similar sleeve over the overlapping ends of the conductors to be joined and twisting the sleeve with the ends of the wires contained therein, thereby making a tight mechanical and 10 a good electrical connection between the ends of the conductors.

It is frequently necessary to splice conducting wires in a relatively confined space or to splice wires which lie closely adjacent other live conductors. Under these circumstances an ordinary 15 clamp type wire splicing tool having the handles fixedly joined to the die is difficult and dangerous to manipulate. I have therefore provided an improved sleeve twisting tool in which 20 a ratchet connection is utilized between the die and the handle.

It is thus an object of my invention to provide an improved ratchet type sleeve twisting tool which is simple in construction, will be durable, and which may be economically produced.

A further object of my invention is to provide an improved ratchet type sleeve twisting tool in which the dies may be easily and securely clamped around the sleeve and conductors.

30 A further object is to provide an improved ratchet type sleeve twisting tool in which a single die may be utilized for a plurality of different sizes of sleeves, and in which any one of a plurality of dies of different sizes may be used with 35 a single handle and ratchet mechanism.

Other objects will appear from the following description, reference being had to the accompanying drawings, in which:

Fig. 1 is an elevation of the wire splicing tool 40 shown in operative position;

Fig. 2 is a side elevation of the sleeve engaging dies, portions thereof being broken away to show the clamping arrangement;

Fig. 3 is a view similar to Fig. 2 showing the 45 reverse sides of the dies;

Fig. 4 is a fragmentary elevational view of the ratchet socket head;

Fig. 5 is an elevation of the ratchet socket with 50 one of the side plates removed;

Fig. 6 is a transverse sectional view taken on the line 6—6 of Fig. 1;

Fig. 7 is a front elevation of a modified form of ratchet type sleeve twister;

Fig. 8 is a side elevation of the major portion 55 thereof taken on the line 8—8 of Fig. 7;

Fig. 9 is a detail sectional view showing the means for clamping and locking the dies together;

Fig. 10 is a side elevation of the ratchet head;

Fig. 11 is a sectional view taken on the line 60 11—11 of Fig. 7; and

Fig. 12 is a transverse sectional view taken on the line 12—12 of Fig. 7.

The sleeve twisting tool shown in Fig. 1 comprises a pair of dies 20 and 22, the ends of which 65 are pivoted to the ends respectively of a link 24. The die 20 has a slot 26 formed therein to receive the head 28 of a locking bolt 30, which is pivoted on a shouldered rivet 32 secured to the die 20. The threaded shank 34 of the locking bolt 70 is adapted to project through a slot 36 in the end of the die 22. A nut 38 is threaded on the shank 34 of the locking bolt, the nut having a handle arm 40 formed integrally therewith. The dies 20 and 22 each have sleeve engaging recess 75 42 which is complementally shaped to engage a sleeve 44 and press it tightly about the conductors 46 and 48. On their opposite faces the dies have similar recesses 50 for engagement with a sleeve of larger size. Each of the 80 dies has an irregularly shaped sidewardly extending lug 52. When the dies are clamped over a sleeve as shown in Fig. 2, these lugs together form a hexagonal sidewardly extending boss. The lugs 52 are relieved at 54 so as normally not to contact with the sleeve. Similar irregularly shaped 85 sideward projections 56 are formed on the opposite sides of the dies. It will thus be apparent that the locking nut 38 may be loosened and the bolt swung upwardly out of the slot 36, whereupon 90 the die 20 (Fig. 3) may be swung in the direction of the arrows to the dotted line position, and the bolt again engaged in the slot 26 and tightened to clamp the die about a larger size sleeve, in this instance utilizing the recesses 50 in the die 95 for engagement with the sleeve. When in this position the lugs 56 will together form a hexagonal sidewardly extending boss.

The sidewardly extending hexagonal bosses formed by the lugs or projections 52, and by the 100 lugs 56, are adapted to engage in the hexagonal socket opening 60 formed in a ratchet wheel 62. The ratchet wheel has a sidewardly extending hub 64 journaled in the side plate 66 and a hub 68 on its opposite side journaled in a side plate 70. The side plates 66 and 70 are secured to a handle 72 by a plurality of screws 74. The ratchet wheel 62 has a plurality of teeth 76 formed thereon which are adapted to be engaged by a spring 105 pressed pawl 78 which is reciprocable in a T- 110

headed slot 80 formed in the handle 72, the pawl being retained in said slot by the side plates 66 and 70. The ratchet wheel 62 has a slot 82 extending from its periphery to the socket 60 and the side plates 66 and 70 have slots 84 which are adapted to register with the slot 82 as indicated in Fig. 5. The slots preferably extend at an angle to the major axis of the tool so that the tool may hang suspended from a wire even though the slots 82 and 84 be aligned. The handle 72 is preferably covered with a layer 86 of insulating material and is preferably provided with a hole 88 for permitting attachment of the tool to the lineman's belt.

15 In using the tool the dies 20 and 22 are first clamped about the end of the sleeve which has been placed over the overlapping ends of the wires to be spliced, and clamped sufficiently tightly to deform the sleeve about the wires, as shown in Figs. 2 and 3. The ratchet wheel 62 is then rotated until its slot 82 is in alignment with the slots 84 so that it may be passed over one of the conducting wires and pushed sidewardly to engage the hexagonal projection formed by the lugs 52 in the socket 60. The other end of the sleeve 44 may be engaged by a similar tool or by a more simple plier type of clamp. Thereafter, by swinging the handle back and forth, the sleeve may be twisted to the form shown in Fig. 1, thereby tightly splicing the ends of the wires, whereupon the tool may be quickly and easily disengaged from the wire.

30 The splicing tool shown in Figs. 7 to 12 inclusive is generally similar to that above described, but is of a construction well suited for making smaller tools of this general type. The dies 90, 92 are pivoted to the ends respectively of links 94 and are arranged to be clamped together over a splicing sleeve by a locking cam 96 formed integrally with a handle 98 and pivoted on a pin 100. The ends of the pin 100 are riveted in links 102, which are in turn pivotally connected to the die 90. The locking cam 96 is adapted to engage in a shallow recess 104 formed in the die 92. The die halves 90, 92 have transverse grooves formed in their faces which together present a plurality of figure 8 shaped openings 110 in which the splicing sleeve 112 together with its conductors 114 may be clamped when the locking handle 98 is moved to the position in which it is shown in Fig. 8. The openings 110 are preferably of different sizes to accommodate various sized sleeves. The dies are provided with pairs of holes 116, 118, and 120, one pair for each of the sleeve-receiving openings 110. The ratchet stop, best shown in Figs. 7, 10 and 11, preferably comprises a forging 122 having a handle 124 formed integrally therewith. The body of the forging is bored and counter-bored to provide a cylindrical recess 126 and a transverse opening 128. A ratchet wheel 130 has a sidewardly extending hub portion 132 journaled in the opening 128 and has a plurality of teeth 134 arranged to be engaged by a pawl 136 which is guided in a hole 138 drilled in the body forging 122. The plunger pawl 136 is pressed toward the ratchet wheel by a compression spring 140 which rests within a socket 142 formed in a handle 144. The latter may be threaded or otherwise suitably secured to the body forging 122. The ratchet wheel is held within the counter-bore 126 by a plate 146 which may be welded or otherwise suitably secured to the body forging 122.

75 The ratchet wheel 130 has a pair of pins 148 threaded therein, these pins being properly

spaced on a diametral line of the ratchet wheel so as to be engageable in one of the pairs of holes 116, 118, 120 formed in the dies 90 and 92, depending upon the size of the connection sleeve being twisted. It will be noted that the body 80 forging 122 has a slot 150 and the ratchet wheel a similar slot 152 which slots, when in registry, permit the tool to be passed over a wire or sleeve, whereupon the tool may be moved sidewardly to couple with a pair of dies 90, 92 which have been previously rigidly clamped to the sleeve to be twisted.

90 The tool is used in the same manner as above described with reference to the tool shown in Figs. 1 to 6 inclusive.

95 The use of the pins 148 instead of a hexagonal boss on the dies makes it possible to provide a single die with a plurality of jaw parts for engagement with sleeves of different sizes and yet have the turning movement about the axis of the sleeve being twisted.

100 While I have shown and described particular embodiments of my invention it will be readily understood by those skilled in the art that variations may be made in the constructions disclosed without departing from the basic features of my invention. I therefore do not wish to be limited to the precise construction disclosed but wish to include within the scope of my invention all such modifications and variations which 105 will readily suggest themselves.

110 What I claim as new and desire to secure by United States Letters Patent, is:

1. A wire splicing tool comprising a pair of cooperating dies, means for clamping said dies about a wire connecting sleeve to compress the latter about the wires, a handle having a head, a ratchet wheel mounted for rotation in said head, a pawl engageable therewith, said head and ratchet wheel having slots therein to permit the wire to be spliced to pass therethrough to substantially the center of said ratchet wheel, and quickly detachable interengaging means on said dies and on said ratchet wheel for rotating the former by rotation of the latter. 115

120 2. A wire splicing tool comprising a pair of cooperating dies, each having a plurality of complementary wire connecting sleeve engaging surfaces, means for clamping said dies about a connecting sleeve, a plurality of pairs of holes in said dies one for each of said complementary sleeve engaging surfaces, a rotating ratchet mechanism having a ratchet wheel, and a pair of pins projecting from the side of said ratchet wheel and engageable in any one of the said pairs of holes 125 in said dies whereby said dies may be rotated by means of said ratchet mechanism. 130

135 3. In a wire splicing tool, the combination of a handle having a head, said head having a wire receiving slot formed therein, a ratchet wheel rotatably mounted in said head and having a wire receiving slot formed therein, a pawl engageable with said ratchet wheel, a pair of dies constructed and arranged to be clamped to a wire connecting sleeve, and quick-detachable interfitting non-rotative means for connecting said dies to said ratchet wheel for rotation thereby. 140

145 4. In a wire splicing tool, the combination of a pair of dies, a link pivotally connecting said dies, clamping means to draw said dies together about a wire connecting sleeve, and lugs extending sidewardly from said dies, said lugs being shaped to form a regular polygon when said dies are clamped together over a sleeve. 150

5. A wire splicing tool comprising a handle, a pair of plates secured one on each side of said handle and having similar openings formed therein, a ratchet wheel having sidewardly projecting hub portions journaled in the openings in said plates, a spring pressed pawl engageable with said ratchet wheel, said ratchet wheel having a central polygonal opening and said ratchet wheel and plates having slots adapted to register to permit a wire to be passed transversely into the central opening in said ratchet wheel, and a pair of dies having means for clamping them to a connecting sleeve, said dies having sidewardly extending lugs forming a polygonal projection cooperable with the central opening in said ratchet wheel.
